(57) **CLAIM**

The ornamental design for a coax cable connector, as shown and described.

DESCRIPTION

FIG. 1 is a top plan view of my new design of a coax cable connector;

FIG. 2 is a bottom plan view thereof;

FIG. 3 is a top perspective view thereof, in a closed position;

FIG. 4 is a bottom perspective view thereof, in an open position;

FIG. 5 is a top perspective view thereof; and,

FIG. 6 is a front elevation view thereof, with the rear elevation view being a mirror image thereto.
